CRATE

Filed Oct. 28, 1922

2 Sheets-Sheet 2

UNITED STATES PATENT OFFICE.

FRED C. BARTLETT, OF CROMWELL, IOWA.

CRATE.

Application filed October 28, 1922. Serial No. 597,536.

To all whom it may concern:

Be it known that I, FRED C. BARTLETT, a citizen of the United States, residing at Cromwell, in the county of Union and State 5 of Iowa, have invented certain new and useful Improvements in Crates, of which the following is a specification.

This invention relates to knock-down crates and is intended more particularly for 10 use in shipping hogs or other live stock. The object of the invention is to provide a crate of inexpensive construction which may be produced at a low cost and which may be readily collapsed and brought within a 15 small compass to economize space in storage or return shipment, and another object of the invention is to provide a knock-down or collapsible crate which, when set up for use, will be rigid and not apt to be prematurely 20 or accidentally collapsed. The stated objects and other objects which will incidentally appear in the course of the following description are attained in the use of such a construction as is illustrated in the accompanying drawings, and the invention resides in certain novel features which will be 25 particularly pointed out in the claims following the description.

In the drawings—

Figure 1 is a perspective view of one end 30 of the crate as it appears when set up for use;

Fig. 2 is a similar view showing the crate in knocked-down or collapsed condition, the 35 intermediate portions of the side members of the crate being broken away in order that substantially the entire portion of the crate may be illustrated;

Fig. 3 is an enlarged front elevation of 40 one corner of the end frame;

Fig. 4 is an enlarged longitudinal section of the same;

Fig. 5 is a perspective view of another corner of the end frame;

Fig. 6 is a perspective view of a corner of 45 the end frame showing the same partly folded to the collapsed form;

Fig. 7 is an enlarged detail perspective view of the clasp by which the braces are held in place when the crate is set up;

Fig. 8 is a perspective view of one end 50 of another form of the crate, and

Fig. 9 is a detail perspective view of a foot or support which may be employed.

The end members of the crate consists pri-

marily of angle irons 1 of proper length, four of such angle irons being employed as is obvious. In the form of the invention illustrated in Fig. 1, the top and the two sides of the crate are constructed of boards or 60 slats 2 which extend longitudinally of the crate and have their ends riveted or otherwise secured to the longitudinally extending webs of the angle iron members of the end frames, and in both illustrated forms of 65 the invention the bottom 3 is a board co-extensive in area with the bottom of the crate.

The several angle iron members of the end frame are connected at their meeting ends by hinges or clasps so that, when the 70 crate is to be collapsed, the said members may be readily folded or swung about each other so as to be brought into compact superposed form. The hinged connections may be conveniently formed by providing a 75 transverse slot 4 in one end member and forming a hook or bead 5 upon the meeting end of the adjoining end member to be engaged through the said slot, as will be readily understood. The transverse webs of the 80 angle iron members are beveled or cut away on inclined lines at their ends, as shown at 6, whereby the said webs may abut and the adjoining members be disposed at a right angle to each other. It will also be readily 85 noted that the slotted end of each member is projected somewhat beyond the beveled end of the transverse web thereof, presenting a tongue 7 so that the hinge connection will be laterally beyond the abutting faces of the 90 frame members and will, therefore, permit the members to be brought into juxtaposition so that they will mutually reinforce and brace each other when the crate is set up for use. The hinge connections are pro-

vided at both lower corners of the end frame and at one upper corner, while at the opposite upper corner, the top frame member 8 is provided with a terminal extension or tongue 9 adapted to pass through the slot 10 provided therefor in the abutting side frame member and provided with a perforation 11 to receive a cotter pin, or other fastening 12. The top frame member 8, in the form illustrated in Fig. 1, is also provided with a slot 13 extending lengthwise of the said member at the center thereof to receive a board 14 which constitutes a closure or door for the end of the crate, and this board 14 is inserted downwardly 110

through the said slot so that its lower end will rest upon the bottom 3 of the crate against the inner face of the vertical transversely extending web of the bottom frame member 15. Braces are provided to prevent lateral spreading of the sides of the crates, and these braces consist of stout wires or rods 16 which have their end portions diverging from their centers and provided 10 with terminal eyes or hooks 17 adapted to be engaged through openings 18 in the transverse webs of the side frames 1 and 19. The said braces are shaped to present short straight portions at their centers and upon 15 the central straight portion of one brace is fitted a clasp or hook 20 which is adapted to engage around the corresponding portion of the other brace, as shown in Fig. 1, whereby the braces will be held together and will 20 effectively resist any tendency of the sides of the crate to spread apart. In Fig. 1, I have shown only the front end of the crate, but it will be understood that the back end of the crate is a duplicate in construction of 25 the front end thereof so that illustration of the same is unnecessary.

When the crate is to be used, it is set up, as shown in Fig. 1, and the back end is completed by the insertion of the board or 30 door 14 and the engagement of the clip 20 with the braces 16. The hog or other animal is then driven into the crate through the front end thereof and the front door or closure 14 is inserted, after which the braces 16 35 are swung to position across the end of the crate and fastened in that position by the adjustment of the clamp or hook 20. The crate may then be loaded onto a wagon or truck and the animal transported to market.

40 When the animal has been delivered, the crate may be readily collapsed or knocked down so as to be returned to the original shipper. To accomplish this end, the key or other fastening 12 is withdrawn so that 45 the side frame member 1 may be swung away from the top frame member 8, it being understood, of course, that the door 14 has been previously withdrawn and the clamp 20 disengaged from the brace with which its 50 free end co-operates. The top frame member 8 is then swung about its hinge connection with the side frame member 19 so as to lie against the latter at the outer side of the same. The said top frame member 8 55 may then be placed upon the ground or upon the floor of a car or other vehicle in which the return shipment is to be made, the bottom of the crate being thus brought into an upright position. The side frame member 1 may then be swung about its hinged connection with the bottom frame member 15 so as to lie against the outer side thereof, after which the members 1 and 15 may be 60 swung downwardly into alignment with the members 19 and 8, as shown in Fig. 2. The 65

braces 16 may then be swung over upon the side members, whereupon the device will be ready for the return shipment. It will be readily noted that, in the collapsed condition, the crate occupies very little space so that 70 a large number may be returned at one time with minimum changes for transportation. Furthermore, a large number of the crates may be stored in a barn or other store room without occupying a great part of the space 75 therein so that they will be out of the way until again needed for use. If a further economy of space is desired, the several end frame members may be readily detached inasmuch as the members of the hinge connections 80 may be easily disengaged and the sides and top of the crate may then be easily piled upon the bottom of the crate.

In the form of the invention illustrated in Fig. 8, the top, sides and ends of the crate consist of wire-mesh fabric or interwoven light rods, as indicated at 21, instead of the slats or boards 2 shown in Fig. 1. The end frame members are constructed of angle iron and hingedly connected at their ends in the same manner as the end frames of the previously described form of the crate, but in addition to these angle irons, I employ the flat bars 22 which have their ends secured to the respective end frame members and 90 extend longitudinally of the crate so as to provide a rigid longitudinal edge member to which the fabric panels may be attached. I have also shown the door as consisting of a substantially rectangular frame of flat bars 100 23 to which the edges of the woven fabric are secured and have also shown it as hingedly connected to the bottom of the end frame by eyes or rings 24 fitted through 105 openings provided for that purpose in the respective frame members. The braces 25 in this embodiment of the invention have their lower ends suitably engaged with the bottom member of the end frame and their upper ends engaged over suitable pins on the top member of the end frame. Pivoted clip plates or latches 26 are provided upon the top member of the end frame to extend over the pins and thereby prevent accidental release of the braces, and a similar plate 27 110 is mounted upon the top member of the end frame at the center thereof to engage over the top edge of the door and aid the braces in preventing accidental opening of the door. 115

The crate may rest directly upon the bottom members of the end frames, but if it be desired to have the crate supported with its bottom above the bottom of the wagon or other supporting structure, feet 28 may be provided. One of these feet is illustrated in Fig. 9 and consists of a suitably shaped casting having an opening 29 through one end to permit the insertion of a fastening device into the bottom of the crate and having its opposite end offset downwardly, as 120 125 130

shown at 30, so as to provide a lug which may rest directly upon the floor of the wagon or other support.

In both illustrated forms of the invention, it will be noted that the structure provides for a free circulation of air through the crate so that in hot weather the discomfort of the animals will be minimized, and this open construction facilitates cleaning of the crate and the destruction of any germs which may have found lodgment therein. The open construction illustrated also reduces the weight from what it would be if all the sides and top were solid as is obvious. The crate may be produced at a low cost and, when set up for use, it will be rigid so that it may be handled without requiring the exercise of any particular care to guard against collapse, although, as will be readily understood from what has been said, it may be easily and quickly knocked down or collapsed for return shipment or for storage so that a single crate may be used for an indefinite period.

It will, of course, be understood that changes may be made in the minor details of construction without departing from the spirit or scope of the invention as the same is defined in the following claims. The door may be provided at one end only and may be inserted through the side instead of through the top and the form shown in Fig. 8 may be equipped with a sliding door instead of a hinged door if preferred.

Having thus described the invention, what is claimed as new is:

1. A knock-down crate consisting of end frames each composed of a plurality of frame members hingedly connected at their meeting ends, means for preventing separation of said frame members when the crate is set up for use, side, top and bottom members secured to and extending between the corresponding members of the end frames, and closures for the end frames.

2. A crate comprising end frames each consisting of a plurality of angle bars having the ends of their transversely extending webs beveled whereby they may abut and

permit the members to be assembled in right angular relation, hinge connections between the meeting ends of said angle bars, a bottom having its ends secured to the longitudinally extending webs of the bottom member of the end frames, side members secured to the longitudinally extending webs of the side members of the end frames, a top secured to the longitudinally extending webs of the top members of the end frames, closures for the end frames, and means carried by the end frames to prevent collapse of the crate when the same is set up.

3. A crate comprising end frames each consisting of a plurality of angle bars, each angle bar being provided with a transverse slot in one end of its longitudinally extending web and at its opposite end with a transversely disposed hook adapted to be engaged through the slot in the meeting end of an abutting angle bar whereby the several angle bars will be hingedly connected, a releasable connection between the meeting ends of two of the angle bars, a top, bottom and sides secured to and extending between the corresponding members of the end frames, closures removably fitting in the end frames, and means carried by the end frames to retain said closures in closed position and prevent spreading of the end frames.

4. A crate comprising end frames each consisting of a plurality of angle bars having the longitudinally extending webs of adjacent angle bars hingedly connected at their meeting ends, a top, a bottom and sides secured to and extending between the corresponding members of the end frames, closures fitting through the top members of the end frames and resting upon the bottom members thereof, bracing rods having their ends engaged in the side members of the end frames and converging toward their centers, and a locking connection mounted upon the central portion of one of said bracing rods and detachably engaging around the central portion of the other bracing rod.

In testimony whereof I affix my signature.

FRED C. BARTLETT. [L.S.]
